UNITED STATES PATENT OFFICE

163,998

HIGH CHAIR

Bertis F. Hamilton, Columbus, Ind.

Application September 10, 1949, Serial No. 4,944

Term of patent 14 years

(Cl. D15—8)

To all whom it may concern:

Be it known, that I, Bertis F. Hamilton, a citizen of the United States, residing at Columbus, Bartholomew County, Indiana, have invented a new, original, and ornamental Design for a High Chair, of which the following is a specification, reference being had to the accompanying drawing, forming part thereof.

Fig. 1 is a top plan view of a high chair embodying my new design with the tray removed in order to illustrate the shape of parts under the tray; and Figs. 2, 3, and 4 are, respectively, a top plan view, a front elevation, and a side elevation of the high chair with the tray in place.

I claim:

The ornamental design for a high chair, as shown.

BERTIS F. HAMILTON.
